US0D1098263S

(12) **United States Design Patent** (10) Patent No.: **US D1,098,263 S**
(45) Date of Patent: ** Oct. 14, 2025

(54) **PRINTER**

(71) Applicant: **ZHONGSHAN BAOLITU ELECTRONIC TECHNOLOGY CO., LTD.**, Guangdong (CN)

(72) Inventors: **Chen Liang**, Guangdong (CN); **Dongming Lin**, Guangdong (CN)

(**) Term: **15 Years**

(21) Appl. No.: **29/947,136**

(22) Filed: **Jun. 13, 2024**

(30) **Foreign Application Priority Data**

Dec. 14, 2023 (CN) 202330825471.6

(51) LOC (15) Cl. **14-02**

(52) U.S. Cl. ..... **USPC D18/19**

(58) **Field of Classification Search**
